Primary Examiner — Paula Greene

(57) **CLAIM**

The ornamental design for headphone ear cups, substantially as shown and described.

DESCRIPTION

FIG. 1 is a perspective view of a set of headphone ear cups as seen from the front and left side;
FIG. 2 is a perspective view thereof as seen from the front and right side;
FIG. 3 is a front view thereof;
FIG. 4 is a back view thereof;
FIG. 5 is a left side view thereof;
FIG. 6 is a right side view thereof;
FIG. 7 is a perspective view thereof as seen from the left side and bottom;
FIG. 8 is a perspective view thereof as seen from the right side and bottom;
FIG. 9 is a top end view thereof; and,
FIG. 10 is a bottom end view thereof.
The dotted line portions of the drawings represent environmental structure only and do not form part of the claimed design.

1 Claim, 8 Drawing Sheets
